(57) **CLAIM**

The ornamental design for an augmented reality hat, as shown and described.

DESCRIPTION

FIG. 1 is a first perspective view of the augmented reality hat showing my new design.

FIG. 2 is a second perspective view thereof;

FIG. 3 is a third perspective view thereof;

FIG. 4 is a fourth perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines are for environmental purposes only and form no part of the claimed design. The design shown is not to be limited to any particular size and may be scaled larger or smaller.

1 Claim, 10 Drawing Sheets
